Primary Examiner — Keli L Hill(74) *Attorney, Agent, or Firm* — Banner & Witcoff, Ltd.(57) **CLAIM**

The ornamental design for a housing for wireless device as shown and described.

DESCRIPTION

FIG. 1 is a front perspective view of a housing for wireless device showing our new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the housing for wireless device form no part of the claimed design.

1 Claim, 6 Drawing Sheets(56)
